UNITED STATES PATENT OFFICE.

NOAH BARKER, OF SEEVERS, IOWA.

ARMY FIRST-AID PACKET.

1,169,913.

Specification of Letters Patent.

Patented Feb. 1, 1916.

Application filed November 4, 1914. Serial No. 870,301.

To all whom it may concern:

Be it known that I, NOAH BARKER, a citizen of the United States, residing at Seevers, in the county of Jasper and State of 5 Iowa, have invented a new and useful Army First-Aid Packet, of which the following is a specification.

My invention relates to first aid packets used by soldiers, sailors, hunters and the 10 like.

The object of my invention is to provide a first aid packet of simple, durable, inexpensive and compact construction, which may be readily and easily carried, by means 15 of which the user may readily and easily produce heat without flame, or may produce gas or make a flame fire.

More particularly it is my object to provide a first aid packet for emergency work 20 in the field, for making wet or dry packs, cauteries, hot sponges, hot drinks for treatment of shock, external hemorrhages, etc.

My invention consists in the construction, arrangement and combination of the various 25 parts of the device, whereby the objects contemplated are attained, as hereinafter more fully set forth, pointed out in my claims, and illustrated in the accompanying drawings, in which:

30 Figure 1 shows a side elevation of the casing inclosing a first aid packet embodying my invention. Fig. 2 shows a vertical, central, sectional view through the same. Fig. 3 shows a side elevation of the inner 35 sack. Fig. 4 shows a vertical, sectional view through the outer receptacle, the sack within the receptacle being shown in side elevation.

In the exemplification of my invention 40 shown in the accompanying drawings, I have used the reference numeral 10 to indicate generally a small amount of carbid which is received within a packing 11 of absorbent cotton or other suitable material. The packing 11 and carbid 10 are received 45 in a flexible sack 12 of sterilized gauze or other suitable material, the free end of which is tied at 13 to form a handle 14. The sack 12 is preferably placed in a suitable 50 receptacle 15 in inverted position, as shown in Fig. 2. The receptacle may be made of any suitable material, such as a proper metal for the purpose.

The receptacle 15 is provided with a cover 55 16, which may be sealed on the receptacle by

suitable means 17, such as paint, wax or the like. Around the sack 12 in the receptacle 15 is a suitable packing 18 of absorbent cotton or the like.

My first aid packet may be made of substantially the size shown in the drawings, or of any other size as may be desired. Preferably, however, it is made in small packet form and for a single use.

In the practical use of my improved first aid packet, the device is carried in the knapsack or duffle-bag, or even the pocket.

It is well-known that in case of gun shot or other wounds where the skin is broken, the greater danger commonly results from 70 exposure and infection due to the fact that dirt gets into the wound from soiled clothing or other sources, and from lack of immediate care and attention to the wound. It should be understood that the packing 75 11, sack 12, and the interior of the receptacle 15 are thoroughly sterilized when the packet is put up or assembled. In case the owner of the packet should receive an abrasive wound, the sack 12 may be removed 80 from the receptacle 15, grasped by the handle 14, and held in inverted position. A small amount of water may be poured upon the bottom of the sack 12, and will gradually saturate the upper part of the packing 85 11 until the moisture reaches the carbid, when heat and gas will be produced. Sufficient heat can be produced so that the wound may be cleaned or seared as desired, thereby giving the necessary first aid and 90 leaving the wound in good condition, so that even if the wounded person should not have the immediate attention of a physician, no infection would result.

A gas may be produced and used for any 95 purpose desired, or if flame is desired the packet may be used as shown in Fig. 2 or as shown in Fig. 4. By supplying water slowly to the packet a flame can be produced for heating the water for cleansing 100 the wound or for any other desired purpose.

A sufficient amount of packing is placed around the carbid within the sack 10 to prevent a too rapid generation of gas when water is poured upon the sack and yet to 105 permit sufficient chemical action within the sack to produce heat necessary for properly caring for a wound.

A very small amount of the carbid wrapped in a small portion of the ster- 110

ilized gauze sack 12 may be put into an open wound, and will immediately cauterize the parts and stop the bleeding.

An additional packing 18 is placed around the sack 12 within the receptacle 15 to properly pack the sack and also to cause the gas to generate more slowly where such a slower generation is desired. The additional packing 18, and the sterilized gauze 12, may also be used for dressing a wound if desired.

It will be understood that some changes may be made in the construction of my improved packet without departing from its essential features, and it is my intent to cover by this application any such changes which may be included within the scope of my claims.

Copies of this patent may be obtained for five cents each, by addressing the "Commissioner of Patents, Washington, D. C."

I claim as my invention:

1. In a first aid packet, a sterilized gauze 20 sack, a suitable absorbent packing therein, carbid in said packing, absorbent packing around said sack, a rigid receptacle therefor, a removable cover on said receptacle, and means for sealing said cover. 25

2. In a first aid packet, a flexible receptacle having one end tied to form a handle, carbid therein, packing around said receptacle, and around said carbid, and a receptacle for said parts having a sealed removable cover. 30

Des Moines, Iowa, October 20, 1914.

NOAH BARKER.
